UNITED STATES PATENT OFFICE.

SAM SORENSEN, OF HOUSTON, TEXAS.

RAIL-CONNECTING PLATE.

Application filed December 4, 1925. Serial No. 73,123.

My invention relates to connecting means to be employed in securing together the ends of adjacent rails in the constructing of railway tracks.

5 It is an object of the invention to provide a connecting device for use between the rail ends to secure them together so that no relative vibration or play can take place. It is desired to make a rigid joint wherein the 10 rails are gripped tightly and firmly together to prevent motion of one rail relative to the other. The invention consists in the construction and arrangement of the parts making up the joint which will be hereinafter 15 particularly set out.

Referring to the drawings herewith, Fig. 1 is a top plan view of a rail joint embodying my invention. Fig. 2 is a side elevation thereof, and Fig. 3 is a section through 20 the rail at one side of the joint showing an end elevation of the invention. Like numerals of reference designate like parts in all the views.

The present invention is an improvement 25 upon my prior invention patented February 10th, 1925, Serial No. 1,526,250.

The drawing illustrates the adjacent ends 30 of two rails of an ordinary railway track in which the rail has an upper head 1, upon which the car wheel may run, and having a base 2, the head and base being connected by a web 3. This is the usual and ordinary rail. I provide at the joint a base plate 4, which has in its upper face a channel 5 of 35 the proper width and depth to receive the base 2 of the rail. The walls of the channel above the rail base diverge upwardly, as shown at 6, a shoulder 7 being formed in the plate between the sloping walls 6 and the channel 5, in which the rail base fits. 40 Beyond the longitudinal ridge 8, upon which the walls 6 are formed, the plate is extended laterally at 9, and provided with notches or recesses 10 therein to receive the usual spikes, by means of which the rail is secured to the cross-ties.

The fish plates employed at the rail joint are angular in cross section, somewhat similar to the usual angle iron. Each plate is 45 intended to form a sort of bell crank lever, as will be recognized from Fig. 3. The upper arm 10 of the lever is formed by that part of the plate extending upwardly along the web 3 of the rail, and having an upper 50 end 11 fitting against the web 3 and beneath the head 1 of the rail. Below this upper

end the lever arm is spaced from the web. The angle 12 of the fish plate forms a fulcrum bearing against the rail base, the lower arm of the lever extending outwardly therefrom in an approximately horizontal position. The outer end of the lower arm 13 of the plate is beveled as shown in Fig. 3, to bear against the sloping wall 6 of the ridge 8.

The upper portion 10 of the fish plate is secured to the webs of the rail ends by the usual transverse bolts 14. The lower end of the fish plate is also secured to the base plate by means of cap screws 15. These screws 70 are fitted within an outer notch or recess in the side of the fish plate and into openings in the inner side of the ridges 8 upon the plate and extended downwardly through the plate.

It is contemplated that in operation the weight of a passing train upon the rail 1 will force the rail and the fish plates downwardly under a slight compression so that the outer arms of the fish plates will bear 80 against the diverging walls 6 of the rail channel, thus forcing the arms 13 of the levers formed through the plates, upwardly and thus throwing the upper side 11 of the plate inwardly, and more securely clamping 85 the rail. In this manner, the slight compression due to a passing train acts to more securely grip the rail so that no relative movement of the parts can take place. The effect of this shape of fish plate is to throw the 90 upper end 11 inwardly and bearing down upon the angle or fulcrum 12, holding the rail base firmly against the base plate 4. It has been found that a joint thus made will allow no appreciable movement between 95 the ends of the rails, the joint being entirely without play, so that no appreciable wear occurs at the joint. The advantages of such construction will be apparent to those skilled in the art without further description.

100 What I claim and desire to protect by Letters Patent is:

1. A rail joint including a base plate having an upper channel to receive the rail base, a shoulder at each side of said channel, 105 an upwardly extending ridge at each side of said channel said ridges having downwardly converging walls adjacent said shoulders, fish plates having an upright portion spaced from the rail except at its upper and lower 110 ends, horizontal members on said fish plates contacting with the rail base at one side and

said converging walls at the outer side, and means to secure said fish plates on said rail.

2. A rail joint including a base plate having a longitudinal channel to receive the rail base ends, fish plates angular in cross section, each thus forming a central fulcrum shaped to fit upon said rail base, an upper arm bearing against the rail beneath the head thereof, a laterally extending lower arm and an inclined wall on said base plate arranged to engage said lower arm to force it inwardly and upwardly, whereby said rail is firmly clamped, and means to clamp said fish plates upon said rail, comprising cap screws engaging in recesses in the sides of said plates and in openings in said base plate.

3. In a rail joint, a base plate having an upper rail receiving channel therein, the sides thereof being formed with shoulders at the level of said base and outwardly diverging walls above the said shoulder, angular shaped fish plates each having a lower member bearing on said rail at one side and upon said diverging wall at the other, means securing said fish plates to said rail, said base plate and the outer edge of said fish plate having co-operating openings, and clamping screws in said openings.

4. In a joint for rails having a base member, an upper head and a connecting web, the combination of a base plate, and fish plates angular in transverse section, the central angle of each of which forms a fulcrum, the upper arm shaped to fit beneath said head against said web, and a lower arm adapted to rest on said base plate and be forced upwardly relative to said base plate by weight on said rail, means to clamp said fish plates to said rail, and means to secure said plates to said base plate.

5. A rail joint including a base plate having an upper rail receiving channel therein, the sides of said channel diverging upwardly, angular shaped fish plates each having an upright member bearing against the rail at its upper and lower edges and spaced therefrom between said edges and a horizontal member bearing against said diverging walls at its outer edge, said fish plates and base plate having openings along their meeting edges and cap screws in said openings.

In testimony whereof I hereunto affix my signature this 21st day of November A. D. 1925.

SAM SORENSEN.
